UNITED STATES PATENT OFFICE.

ALBERT FERDINAND SHORE, OF NEW YORK, N. Y., ASSIGNOR TO THE SHORE INSTRUMENT & MANUFACTURING COMPANY.

SCLEROSCOPE.

1,121,050.

Specification of Letters Patent. Patented Dec. 15, 1914.

Application filed January 9, 1912. Serial No. 670,150.

To all whom it may concern:

Be it known that I, ALBERT FERDINAND SHORE, a citizen of the United States, and a resident of New York, in the county of New York and State of New York, have invented certain new and useful Improvements in Scleroscopes, of which the following is a specification.

My invention relates to devices for testing the hardness of materials.

It relates furthermore to the class of instruments called "scleroscopes", and particularly to the scleroscope invented by me and set forth in my U. S. Patent, No. 1,962,790, of June 28th., 1910. In this patent I have shown a machine for determining the hardness of materials by measuring on a graduated scale the height of rebound of a miniature tap hammer, or striker falling from a predetermined height onto the surface of the material the hardness of which is to be measured. This small striker falling simply under its own weight, (about 40 grains), always rebounds to variable heights depending upon the hardness or resistance to penetration offered by the material under test, which may be a metal, such as iron, steel, lead or carbon, or any substance capable of taking on a permanent set. In the original scleroscope, set forth in my above-mentioned patent, it was necessary to suck up the small striker by means of one bulb, and then, after opening an inlet valve, another bulb was pressed to release the striker.

In my improved automatic instrument forming the subject matter of the present application, the necessary valves, the suction for the striker and release for the same are alternately operated by one bulb acting on a cam, through the medium of a piston, an adjustable oscillator and ratchets. This reduction from two to one suction bulb, rendering the adjustment automatic is a great advantage, since it leaves the hands more free, and secures more ease and convenience of manipulation.

In the drawings accompanying and forming part of this application: Figure 1 shows a longitudinal section through the parts necessary to an understanding of the invention; and Fig. 2 is a section at right angles to the plane of Fig. 1.

In both figures the lower portion is cut away, as not forming a part of the present invention.

Referring to the drawings; 1 is a transparent tube graduated to a predetermined scale; 2 are the graduations on said scale; 3 is a small piston tap hammer, or striker, sliding in the tube and provided with enlarged portions 4 and 5 snugly fitting the tube and serving as guides for the striker; 6 is a pointed diamond forming the impinging surface of my improved striker; 7 is a hollowed out space in the top of the striker; 65 7^a is a ring-grip for convenience of the operator in carrying and holding the instrument; 8 are a pair of shears-like levers pivoted at 9, and provided at their lower extremities with hooks 10 adapted to be spread out and hold the striker when ready for the test; 11 and 12 are prongs fashioned on the upper ends of the pivoted levers; 13 is a cone-shaped hollow on the head of the plunger 14, and 15 is a spring maintaining the cone surface 13 in gentle contact with the prongs when the striker is suspended on the hooks 10; 16 is a second hollow steel cone suspended on the top of the graduated tube-casing by the spring 17; 17^a is a cylindrical extension piece screwed onto the top of the graduated tube casing; 18 is a plunger sliding in the cylinder 17^a, and actuating the hollow cone 16; the plunger is also provided with a valve 19, with its packing 20 controlling the passing of air to the graduated tube from the top casing 20^a; 22 are vent-holes fashioned in the plunger 18, and putting the tube alternately in communication with the top casing 20^a and with the piston cylinder 33; 21 are vent holes connecting the top casing 20^a with the outer air; 24 is the rod of the plunger 18 having pivoted at its top a small wheel 25; 26 is a cylinder carrying a cam-disk 27; 27^a are ratchets controlling the movements of the cam disk 27; 28 is a lug attached to the driving end of the cylinder 26; to this lug is fastened the adjustable oscillator 29, actuated by the piston 30; 31 is the piston packing, and 32 is a spring controlling the travel of the piston; 33 is the piston cylinder connected by means of the valve 34 and passages 22 with the graduated tube, and through the tube 34^a with the suction bulb 36; 37 is a spring holding the ratchets 27^a in engagement. 38 is a hollow eccentric screw; 39 is a set-screw provided with a cone 40 at its inner end.

The operation is as follows:—In the original scleroscope set forth in my patent

mentioned above, when the striker was down, it was necessary to press one bulb serving only the purpose of lifting the striker, and then to press another to release it. Now, in the present improved automatic instrument, assume the striker to be down, having been dropped in making a test. It will be found impossible to suck up the striker by pressing and then releasing the bulb 36, since the valve 19 is unseated, having been forced down by a projection on the cam disk 27, thus furnishing air connection between the casing 20^a and the graduated tube 1. But, pressing the bulb again, moves the piston with its oscillating rod 29, thereby advancing the cam disk one step and allowing the small wheel 25 to seat in a depression of the cam disk. Under the action of the spring 17 the valve 19 seats itself, shutting off communication of the tube with the outer air. Releasing now the bulb, the partial vacuum thereby produced causes the striker to rise in the graduated tube and the hook-ends 10 of the levers 8 to enter and be held in the hollow space of the top of the striker. Pressing again on the bulb, advances the cam disk one step, brings the wheel 25 under a projection on the cam, forces down the plunger 18, unseats the valve 19, allowing access of air to the tube 1, so that the striker may fall in free air. The descent of the plunger 18 carries the hollow cone 16 downward, forcing its sides into contact with the prongs 12, thereby shutting together the hooks 10 and releasing the striker. The amount of its rebound measured on the graduated scale, determines the relative hardness of the material under test. Pressing the bulb again advances the cam one step, brings the wheel 25 under a projection on the cam disk, thereby allowing the valve 19 to reseat itself. Releasing the bulb causes the striker to again ascend, and the apparatus is ready for use. Should there be trouble in the catch device, owing to the double hooks not being centered with the bore of the tube, the hollow eccentric screw 38 is turned one way or another to suit the glass, while, if the hooks spread too much, the screw 39 is set in farther, thus forcing the cone end 40 between the upper extension arms of the levers. If the hooks 10 do not spread sufficiently, the set-screw is turned the other way.

55 The two cones, while in constant control of the hooks, are of a loose fit and free to float laterally with the said hooks, so that they may readily adapt themselves to the slighter inaccuracies of the graduated glass tube.

Having thus fully set forth and illustrated my invention, what I claim, is:—

1. In a hardness testing device, a specially graduated tube, a very light striker movable freely in said tube, said striker having a

70 hollowed-out head, a pair of pivoted levers each provided with a hook on its lower extension and being provided each on its upper extension with prongs extending at right angles to each other, in combination with means for causing the striker to rise in the tube and engage the hooked ends in the hollowed-out head of the striker.

2. In a hardness testing device, a graduated tube, a very light striker freely movable in said tube, the striker being provided with a hollowed-out head, and a pair of shears-like levers located in the path of the striker having their lower extensions provided with hooks, the upper extension of each lever having two prongs extending at right angles to each other, in combination with pneumatic means for causing the striker to rise in the tube and with means for expanding the hooks to engage the inner 85 sides of the striker head.

3. In a hardness testing device, a graduated tube, a striker movable freely in said tube, said striker being provided with a hollowed-out head, a pair of shears-like levers 90 located in the plane of travel of the striker, said levers being each provided with a hook end on their lower extensions and with two prongs on their upper extensions projecting at right angles to each other, vertically movable hollow cones for engaging alternately the prongs on each upward extension, and pneumatic means for producing the downward movements of the cones.

4. In a hardness testing device, a graduated tube, a cylinder mounted on the top of the tube, a striker movable in said tube, a plunger provided with air channels movable vertically in the cylinder and controlling the drop of the striker, a valve carried 105 by said plunger and controlling the access of air to the top of the graduated tube, in combination with means for causing vertical movement of the plunger in the cylinder.

5. In a hardness testing device, a graduated tube, a striker movable freely in said tube and provided with a hollow head and a diamond impinging point, expansion hook levers arranged in the paths of the striker, projections fastened on the upper extensions 115 of the levers, a pair of spring-controlled hollow cones engaging alternately the lever projections, and pneumatic means for controlling the upward movement of the striker and the downward movement of the hollow 120 cones.

6. In a hardness testing device, a graduated tube, a striker movable freely in said tube, a pair of hook levers for holding the striker at a fixed height, a cylinder located 125 above and communicating with said tube, a plunger movable vertically in the cylinder, a pair of spring-controlled floating hollow cones movable with the plunger, and a cam disk engaging the top of the plunger and 130

controlling the vertical movements of the plunger, in combination with pneumatic means for moving the cam disk and controlling the rise and descent of the striker.

- 5 7. In a hardness testing device, a graduated tube, a striker freely movable in said tube, a means for holding the striker in a fixed position, downwardly movable plunger adapted to operate the holding means to release the striker, in combination with a single pneumatic bulb controlling the rise of the striker and the downward movement of the plunger.
- 10 8. In a hardness testing device, a graduated tube, a striker freely movable in said

tube, a pair of shears-like hook levers located in the path of the striker and adapted to engage the same, means for regulating the position of the levers relatively to the center of graduated tube, and means for controlling the spread of the hook lever extensions, substantially as set forth.

Signed at New York in the county of New York and State of New York this 27th day of December A. D. 1911.

ALBERT FERDINAND SHORE.
